ATTORNEY

UNITED STATES PATENT OFFICE.

JOHN J. OLSON, OF BELVIEW, MINNESOTA.

COMBINED SHIRT AND TROUSERS SUPPORTER.

Specification of Letters Patent.

Patented Aug. 6, 1918.

1,274,582.

Application filed October 20, 1917. Serial No. 197,658.

To all whom it may concern:

Be it known that I, JOHN J. OLSON, a citizen of the United States, residing at Belview, in the county of Redwood and State of Minnesota, have invented certain new and useful Improvements in Combined Shirt and Trouser Supporters, of which the following is a specification.

This invention relates to a combined shirt and trousers supporter.

The object of the invention is to provide simply constructed and efficient invisible trousers supporters for use in connection with a shirt constructed to coöperate therewith so that the supporter and shirt will be held in proper relation to each other.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a front elevation of a shirt and trousers supporter constructed in accordance with this invention, parts being broken out for convenience in illustration,

Fig. 2 is a rear elevation thereof,

Fig. 3 is an enlarged detail elevation taken from inside the shirt and trousers showing the connection of the supporters with the trousers, and

Fig. 4 is a detail sectional view taken on the line 4—4 of Fig. 1.

In the embodiment illustrated, an outside shirt 1 is shown having loops 2 arranged on its inner face of the shoulders thereof proximate the neck band N. These loops, which may be of tape of any suitable material, are designed to receive and retain the suspenders to be described.

The back of the shirt has transversely aligned and spaced openings 3 which are preferably finished by buttonhole stitching them to adapt them to resist strains. The openings 3 are preferably arranged longitudinally of the shirt and similar openings 4 are formed in the front thereof, four openings being shown in the front and two in the rear. These openings are positioned at suitable points below the waistline of the shirt and are designed for the passage there-

through of the supporters or suspenders now to be described. The shirt 1 in other respects than those above specified may be of the usual construction.

The suspenders which are designed for supporting the trousers and to be concealed by the shirt are constructed of the usual straps 5, composed of webbing, elastic or other suitable material, crossing each other near their rear ends as is ordinary in devices of this character, while the front ends of the straps 5 are bifurcated as shown at 6 to provide the usual attaching straps. The rear ends of the straps 5 and the free ends of the straps 6 are provided with elongated metal loops 7 of a length corresponding to the width of the straps which they are designed to receive and which are connected with said straps by stitching or other suitable means. Shanks 8 extend laterally from one bar of these loops 7 and are rigidly connected with a tab supporting bar 9 at a point midway the ends of said bar as is shown clearly in Fig. 3. The bar 9 is here shown composed of a strip of metal folded longitudinally between the free edges of which is clamped a buttonhole tab 10, the buttonhole 11 therein being shown arranged longitudinally of the tab and designed to be engaged with a button 12 carried on the inner face of the trousers band, a portion of the trousers being here shown at T. The bar 9 is here shown of a length corresponding to the length of the loop 7 and is spaced from said loop by the neck or shank 8 a sufficient distance to permit the bar and the tab 10 carried thereby to be inserted through one of the openings at the lower end of the shirt, said tab 10 being designed to come on the outside of the shirt while the loop 7 is to remain within the shirt and operates as a stop to prevent the suspenders from passing through the openings 3 and 4. It is of course understood that the tab 10 is carried by each of the ends of the suspender straps as is shown clearly in Figs. 1 and 2 and that the construction of these devices is exactly alike in all cases.

In the use of this device, the straps 5 having been forced through the loops 2 at the shoulders of the shirt and the tabs 10 through the openings 3 and 4 at the lower ends of the shirt the device is ready for use and may be connected with the buttons 12 on the trousers band as is shown clearly in Figs. 1 and 2. An inspection of these fig-

ures will clearly demonstrate that the trousers T while being comfortably supported by the suspenders or supporters, the latter will be completely concealed by the shirt 5 and they will be held in proper relation to said shirt by the loops 2 and the openings 3 and 4.

From the foregoing description, taken in connection with the accompanying drawings, the advantages of the construction and of the method of operation will be readily apparent to those skilled in the art to which the invention appertains and while I have described the principle of operation of the 10 invention together with the device which I now consider to be the best embodiment thereof, I desire to have it understood that the device shown is merely illustrative and that such changes may be made as are within the scope of the claimed invention.

I claim:—

The combination with a shirt having a plurality of transversely alined, longitudinally extending openings below its waist

line, of trousers supporting straps, metal 25 loops engaged with the ends of said straps and of a length greater than the length of the openings and positioned transversely across said openings on the inner face of the shirt when in operative position, whereby 30 said strap ends are prevented from passing through the openings, said loops performing the double function of strap connectors and as stops to prevent the passage of the strap ends to the outside of the shirt, 35 a shank extending laterally from one member of each loop and then through one of the shirt openings, a bar carried by said shank and arranged parallel with said loop, and fastener carrying tabs secured to said 40 bars.

In testimony whereof I affix my signature in presence of two witnesses.

JOHN J. OLSON.
